US00D881911S

(12) **United States Design Patent** (10) Patent No.: **US D881,911 S**
(45) Date of Patent: **** Apr. 21, 2020**

(54) **DISPLAY SCREEN WITH GRAPHICAL USER INTERFACE**

(71) Applicant: **KOMAX HOLDING AG**, Dierikon (CH)

(72) Inventor: **Gunnar Donis**, Lucerne (CH)

(73) Assignee: **KOMAX HOLDING AG**, Dierikon (CH)

(**) Term: **15 Years**

(21) Appl. No.: **29/632,951**

(22) Filed: **Jan. 11, 2018**

(30) **Foreign Application Priority Data**

Sep. 29, 2017 (CH) 143524

(51) **LOC (12) Cl.** **14-04**

(52) **U.S. Cl.**

USPC **D14/486**

(58) **Field of Classification Search**

USPC D14/485-495

CPC G06F 3/048-04897

See application file for complete search history.

(57) **CLAIM**

The ornamental design for a display screen with graphical user interface, as shown and described.

DESCRIPTION

The FIGURE is a front view of a display screen with a graphical user interface showing my new design.

The broken lines in the FIGURE showing the display screen illustrate portions of the article and form no part of the claimed design.

1 Claim, 1 Drawing Sheet
